UNITED STATES PATENT OFFICE.

CHARLES OSBORNE, OF NEW YORK, N. Y., ASSIGNOR TO THE WHITING MANUFACTURING COMPANY, OF SAME PLACE.

DESIGN FOR A HANDLE FOR SPOONS OR SIMILAR ARTICLES.

SPECIFICATION forming part of Design No. 33,625, dated December 4, 1900.

Application filed October 12, 1900. Serial No. 32,898. Term of patent 14 years.

To all whom it may concern:

Be it known that I, CHARLES OSBORNE, a citizen of the United States, residing in the city of New York, borough of Manhattan, in the county and State of New York, have invented and produced a certain new and original Design for Handles for Spoons or Similar Articles, of which the following is a specification, reference being had to the accompanying drawings, forming part thereof.

Figure 1 is a view of the obverse face of a handle, showing my design; and Fig. 2 is a corresponding view of the reverse.

The leading features of my design are the fiddle-shaped head margined by long sweeping foliated scrolls inclosing a plain surface and terminating at the top on each side of a small shell ornament and the straight reeded shank joining the bowl and having a foliated ornament on each side at the junction. The stems of the foliated scrolls flanking the shell terminal form a filamented or thread-like margin for the head and extend nearly its entire length. At the junction of the head with the shank the thread or filament effect is interrupted by an incurving foliated ornament on each side inclosing between them a con-

ventional leaf or spray and by a small leaf ornament arranged on the otherwise smoothly curved unbroken outline. The filament motive is carried out in the shank by the reeds on the latter, the simplicity being relieved by short curves arranged transversely in pairs and joining the central reed. The shank swells outward on each side immediately above the bowl and is joined to the latter by easy curves. The swell carries foliated ornaments harmonizing with those on the head. The reverse of the handle is similar to the front face in general appearance; but the ornamentation is less ornate. The central reed on the shank is omitted on this face.

It will be understood that the design is applicable to all classes of table flatware.

I claim—

The design for a handle for spoons or similar articles, herein shown and described.

In testimony that I claim the invention above set forth I affix my signature in presence of two witnesses.

CHARLES OSBORNE.
